By *J. Haas, Jr.* ^{Attorney}

UNITED STATES PATENT OFFICE.

EDWARD F. HARPER, OF PHILADELPHIA, PENNSYLVANIA.

DESIGN FOR A PHONOGRAPH-CABINET.

58,748.

Specification for Design.

Patented Aug. 30, 1921.

Application filed May 14, 1921. Serial No. 469,581. Term of patent 7 years.

To all whom it may concern:

Be it known that I, EDWARD F. HARPER, a citizen of the United States, residing at Philadelphia, in the county of Philadelphia and State of Pennsylvania, have invented a new, original, and ornamental Design for a Phonograph-Cabinet, of which the following is a specification, reference being had to the accompanying drawing, forming part thereof.

Figure 1 is a perspective view, showing my new design.

Fig. 2 is a front elevation, showing my new design.

I claim:

The ornamental design for a phonograph cabinet, as shown.

EDWARD F. HARPER.

Witness:

M. ZUCKER.
